DESIGN FOR A SKI SOCK

Harold R. Anderson, Chelmsford, Mass.

Application April 25, 1945, Serial No. 119,218

Term of patent 14 years

(Cl. D47—7)

To all whom it may concern:

Be it known that I, Harold R. Anderson, a citizen of the United States, residing at Chelmsford, in the county of Middlesex and State of Massachusetts, have invented a new, original, and ornamental Design for a Ski Sock, of which the following is a specification, reference being had to the accompanying drawing forming part thereof.

I claim:

The ornamental design for a ski sock, substantially as shown.

HAROLD R. ANDERSON.
